CORD TWISTER STOPPING MEANS

Seddon C. Nelson, Front Royal, Va., assignor to
 American Viscose Corporation, Wilmington,
 Del., a corporation of Delaware

Application February 10, 1949, Serial No. 75,567

14 Claims. (Cl. 57—80)

1 This invention relates to methods and apparatus for stopping strand-twisting machinery, particularly machinery in which two or more strands are twisted into the form of a plied or doubled construction.

In the operation of twisting machinery, particularly machinery in which two or more strands are twisted simultaneously to produce a cord, maintenance of the strands at uniform tension is highly important in order to produce a symmetrical cord. In the event of substantial variation in the tension, it is desired that the machine be stopped in order to remove the source of difficulty and thus prevent further mechanical trouble as well as inferior cord or thread. Various stopping devices sensitive to strand tensions are available as stopping means for twisting machines. Breakage of a single strand which does occur for this or any other reason is difficult to detect since twisting machinery on account of its closely built structure, is not equipped with breakage detection and stopping devices with respect to each strand, or devices which may detect a broken strand in the twisted cord. It is highly desirable, therefore, to be able to detect the breakage of a single strand in a cord or doubles twister so as to stop the machine and avoid the consequent loss of the strand, and the labor and time needed to bring the machine back into operation in such emergencies.

It is an object of the invention to provide means for stopping strand-twisting machinery operating within a desired tension range when the tension becomes either greater or less than the range. It is another object of the invention to provide a means for stopping a multiple strand twister when a single strand breaks. Still another object is to provide a stopping device through which the cord or strand may pass while its tension varies within a range predetermined without producing fluctuations in the position of the device. An object also is to stop the twister spindle just before the strand runs entirely off of the supply package on the spindle so as to avoid relacing of the machine. It is also an object to provide a simple stopping device which may be readily installed on existing equipment. Other objects, features, and advantages will become obvious from the following description of the invention and the drawing illustrative thereof.

In the drawing,

Fig. 1 is a diagrammatic view of one embodiment of the invention;

Fig. 2 is a side view of apparatus illustrated in Fig. 1;

2 Fig. 3 is a pictorial view of a modified stopping device; and

Fig. 4 is a pictorial view of still another modification.

5 According to the invention, a strand-handling machine may be stopped by passing the strand around an element of a device comprising a movable member supporting a pulley, said member having a neutral position permitting operation of 10 the machine and being movable under the combined influence of the tension in the strand and the tension exerted by resilient members 15 each of which control the movement of the member in a distinct range of movement extending in 20 opposite directions from the neutral position. The resilient members are so adjusted and set that movement of the member occurs only when the tension in the cord acting on the member exceeds or becomes less than that of a predetermined range. Deviation from the neutral position results in actuating a mechanism for stopping the machine.

Figs. 1 and 2 illustrate a machine for forming 25 a cord from two separate strands. A supply package 8 of one of the strands is supported concentrically about a twisting spindle 10; a supply package 12 for the other strand is supported independently of the spindle 10 on another portion of the twisting apparatus. The tail winding 30 of the supply package 12 may be connected to the leading end of a reserve supply package 14 supported in close proximity thereto. A yarn strand 17 from the supply package 12 passes through guides 15 and 16 to a tension device 18 supported 35 above a cover 19 supported on a package holder 21 enclosing the package 8. A shroud 20 prevents the balloon 24 formed in the strand 17 from interfering with balloons of neighboring machines. After leaving the tension device, the 40 strand passes through a thread guide 23 into a balloon 24 formed in the strand by a rapidly rotating flyer 26. After passing through the eye 27 of the flyer, the strand enters a slot or bore 29 through the side of the spindle shaft 10 and passes 45 downwardly through the hollow spindle shaft 10.

The strand 30 passes from the package 8 upwardly into a tension device 32 supported above the package 8 in axial relationship with the spindle shaft 10 into which it passes. The tail 50 end of the strand 30 stored in the package 8 (the last portion of package to leave the package holder 21) is secured to a resilient anchor or spring fastened on the holder for a reason hereinafter explained. The device 32 is adjusted to 55 impart approximately the same tension to the

strand 30 as produced in the strand 17 by the tension device 18. The strands 17 and 30 pass together in parallel untwisted arrangement from the slot 29 downwardly through the rapidly rotating shaft 10 to an idler roll 35 mounted on a bracket 36 extending from the spindle 10. The axis of the roll is preferably at right angles to that of the spindle. The parallel strands 17 and 30 pass at least once around the roll 35 and then around a pulley 37 secured to the machine-stopping device with which the invention is concerned. As the support 36 for the roll 35 is integral with or fixed to the shaft 10, the roll 35 rotates on its own axis and turns with the spindle 10 on the axis of the spindle.

A twist is produced in the strand 17 as it leaves the tension device 18; likewise a twist of similar direction and degree is imparted to the strand 30 as it passes from the tension device 32 into the top of the spindle shaft 10. The twist imparted to the strands may be either S or Z depending on the direction or rotation of the flyer. However, the twist imparted to the strands while separated may be considered a false twist since the strands are twisted into cord in the opposite direction while passing between the roll 35 and the pulley 37. The resulting cord passing from the pulley 37 toward a withdrawal device 39 contains strands which are twisted about each other but in which the individual filaments have the same degree of twist with respect to the strand in which they occur as when they left the supply packages 8 and 12.

Device 39 pulls the strands, and the cord into which they are formed, through the twisting apparatus. It comprises two rolls 41 and 42 having axes canted with respect to each other to cause the thread to advance along their surfaces and to avoid friction or abrasive effects on the cord. The device 39 may be driven from a power take-off 44 driven by the spindle shaft 10. The power takeoff 44 may be employed also to drive a flyer 46 of a cord winding and twisting device 47 through a bevel gear drive 49.

A stopping device according to the invention may comprise the assembly shown in Fig. 1 including a lever 50 pivotably supported at 52 near one end; the pulleys 37 is rotatably mounted at the other end. The tension in the cord passing around the pulley urges the lever in a direction about the pivot 52 in opposition to tension springs 54 and 55 which control the action of the stopping device. The device as illustrated in Figs. 1 and 2 is in its normal operating position in which a lever 58, which pivots at 60, bears against or rests upon a stop or detent 59. This device is actuated only by large fluctuations in the tension of the cord which passes around the pulley 37. Examples of fluctuations of the severity required to operate the device are, the drop in tension produced when either or both of the strands 17 and 30 break, and the increase in tension produced when all of the strand 30 is withdrawn from the package 8, said increase in tension occurring when the transfer of the strand 30 through the machine is stopped by the tail end of the package being tied to the holder. By operation of the stopping device the twister is stopped until the package can be replaced. In the latter case, replacing of the twisting machine is avoided. Tension in the cord, if of sufficient magnitude, moves the lever 50 about the pivot at 52 in opposition to one or both of the tension springs 54 and 55. The spring 55 is set or adjusted to greater tension than the spring 54. Movement of the lever

in either direction about the pivot 52 results in movement of either one or two rods or links 56 and 57 pivotably attached thereto toward a switch button 64 of the switch 65. A microswitch is found very satisfactory for this purpose since only small movement of the links 56 or 57 and the lever 50 is required to obtain actuation of the switch.

As an important feature of the invention movement or fluctuation of the element in contact with the strand (such as the pulley 37 mounted on the lever 50) is avoided regardless of fluctuations in the tension of the cord unless the tension in the strand goes below a predetermined minimum or above a predetermined maximum. To obtain this result, the movement of lever 50 is controlled in a manner such that it moves only when the tension of the cord exceeds or falls short of the predetermined range for which the device is set. In the embodiment just described, the arrangement of the device is such that when the desired range of tension variation in the cord is exceeded, the stronger spring 55 is extended by movement of the lever 50 while the spring 54 remains at constant length because of a tie-rod 62 in slip-connection with the levers 50 and 58 and exerts no additional effect in the operation of the device. When the tension in the cord drops below the operating tension range, the spring 55 is held to constant length by the engagement of detent 59 by the lever 58 and is therefore rendered ineffective. The spring 54 pulls the lever 50 downwardly when the cord tension is less than that of the desired operating range. The spring 54 is adjusted to a lesser strength or tension than the spring 55 to an extent which corresponds to the range of tension covering the normal variation in the tension of the cord through which it is desired that the stopping device be inactive.

The opposing forces, i. e., the force originating in the cord and that produced by the springs 54 and 55, are applied to the lever at unequal distances from the fulcrum or pivot 52 of the lever 50. The opposing forces are therefore inversely proportional to the distances of their points of application from the pivot 52; and the mechanical moments which they produce about the pivot 50 are taken into account when providing the desired tensile or compression forces to be applied in opposition to cord tension to operate the device. Force originating in the spring 55 and producing a moment along the lever 50 is transmitted as a result of the connection of the spring 55 with the lever 58 and interconnection of the levers 50 and 58 by the extended spring 54 and the tie-rod 62 which share the force being transmitted. The moments exerted on the lever 50 by the cord and springs 54 and 55 will be referred to in the following text rather than the actual magnitude of the forces producing the moments.

When the moment of force applied to the lever 50 as the result of tension in the cord is greater than that exerted by the spring 55, the lever 50 tilts, the lever 58 is lifted from the stop or detent 59 by the link 62 and the spring 54, and the spring 55 is stretched. Meanwhile, the link 57 engages the button 64 of the switch 65 to stop the machine. When the cord tension is within the range desired for twister operation, the lever 58 remains at rest on the stop 59 because the moment produced by the spring is greater than that produced by the cord; meanwhile, of course, the spring 54 is in the most extended condition permitted by the tie-rod 62 which limits the maxi-

mum rotation of the levers 50 and 58 from each other. When the cord tension falls below the desired operating range, as when one strand breaks, the spring 55, being adjusted to exert greater tension than the spring 54, holds the lever 58 against the stop while the spring 54 contracts and the lever 50 yields or swings toward lever 58 in accordance with the degree of lessening in the cord tension. As the lever 50 tilts, the link 56 actuates the switch 65.

The lower end of the spring 55 is secured to a fitting 68 adjustable with respect to the rod 67 secured to a stationary support 66. Likewise, the end of the spring 54 nearest the lever 50 is secured to a fitting 69 which may be adjusted with respect to a threaded rod 70 extending through the lever 50. In this manner, the tensions of both springs may be adjusted to secure any limits desired to produce moments on the lever 50 which oppose a desired operating range of moments produced by the cord tension applied to the lever 50. For example, it may be desired to operate a machine to produce textile cord at an average cord tension of 1500 grams in a range between 1000 and 2000 grams. Assuming that the cord tension and the spring tension forces are applied at the same point on the lever to eliminate accounting for moments of the lever arms of various lengths and to simplify explanation, a spring 54 is adjusted so that when the tension in the cord drops below 1000 grams, the lever 50 is pulled downwardly in a counterclockwise direction from its normal operating position by the spring 54. The lever 58 although pulled upon by the spring 54, is held against the stop 59 by the stronger spring 55. When the cord tension exceeds 2000 grams, such as when the strand being withdrawn from the package is exhausted and the tail-end tied to the holder 21 produces a severe increase in the tension of the cord passing around the pulley 37, the lever 50 and the pulley 37 are pulled upwardly in opposition to the tension of the spring 55. Springs 54 and 55 therefore permit an operating tension range of 1000 grams corresponding to the difference in the strength or tension to which the two springs are adjusted or set. When twisting several strands to produce a cord, the weaker or less tense spring 54 should be preferably selected, so that the stopping device is operated by the reduction in cord tension which results when one strand breaks at any point along the path of the strand between the supply package to the take-up means for the twisted cord.

Fig. 3 illustrates a modified stopping device which may be used in place of the device described in the foregoing paragraphs. The cord is passed around the pulley 37 supported at the end of a lever 75 which pivots at 71. As in the previously described device of Figs. 1 and 2, small links or rods 56 and 57 operate the microswitch 65. Rotary motion in a clockwise direction of the lever 75 is resisted by a plunger 79 urged toward the lever by a compression spring 80. The movement of the plunger 79 in a direction toward the lever is limited, however, by a nut 82 in threaded relationship with the threaded shank 81 of the plunger. The force required to move the plunger in opposition to the spring 80 may be varied by adjusting the position of a nut 84 relative to the plunger shank 81. In the position illustrated by Fig. 3, the plunger 79 is in its most extended position from a bracket 86 in which it is supported. The lever 75 is shown in a normal operating position wherein it is held against the 78

head 85 of the plunger by tension in the cord passing around the pulley 37.

The clockwise movement of the lever 75 is also restrained by a tension spring 88 which extends from a threaded adjustable eye-fitting 89 secured to a portion of the frame 86 to the eye of a fitting 91 secured to a portion of the lever 75. A relatively large amount of compression is required to move the plunger head 85 toward the frame 86 against the spring 80 compared to the tensile force required to extend the spring 88. Both springs cooperate to restrain a clockwise or upward movement of the lever 75 as shown in Fig. 3. However, if the lever is moved in a counterclockwise direction from the position shown in Fig. 3, the plunger 79 remains in the position shown because of the nut 82 which acts as a stop, and the spring 88 contracts to pull the lever away from the plunger head 85.

For example, if the twister is operated with a normal or average tension exerted by the cord on the pulley 37 of 1500 grams and it is wished to have the machine stop if the tension exceeds 2000 grams or becomes less than 1000 grams, the spring 80 may be selected and adjusted for a compressive strength which exerts a mechanical moment in the lever 75 with respect to the pivot 71 such that it produces 1000 grams force in opposition to the cord tension at the point at which 30 cord tension is applied to the lever 75. Similarly, the spring 88 is selected and adjusted for a tensile strength which exerts such a moment on the lever that 1000 grams of force are produced in opposition to the cord tension at the point of its application. The pull of the spring 88 is applied continuously; the spring 80 opposes the pull of the cord only when the lever is pulled by the cord in a clockwise direction from its neutral or usual operating position. Obviously, two springs 40 80 and 88 in unison provide a 2000 gram force opposing the movement of the lever 75 in a clockwise direction from the position shown whereas, only a 1000 gram pull by the spring 88 opposes movement of the lever in a counterclockwise direction as viewed in Fig. 3. The lever remains stationary until the force applied thereto from the cord exceeds 2000 grams, whereupon the lever moves counterclockwise to actuate the switch 65 by contact therewith of the lever 57, or, the force 45 exerted on the pulley drops below 1000 grams causing the lever 75 to move in a counterclockwise direction and to move the element 56 lengthwise to operate the switch. By this arrangement the cord tension may vary between 1000 and 2000 50 grams without causing any movement in the lever 75 or otherwise actuating the machine-stopping device. The device of Fig. 3 responds to cord tension, and effects stopping of the machine, in the same manner as the earlier described 55 modification of Figs. 1 and 2.

A further modification of the invention is illustrated in Fig. 4 having a switch 65, a pivotably supported lever 75, switch-actuating elements 56 and 57 and a pulley 37 similar to those of the previously described embodiments. However, in the device of Fig. 4, force applied to the lever 75 resulting from tension in the cord passing around the pulley 37 is opposed by two compression springs 95 and 96. The springs urge the plungers 98 and 99 respectively in a direction substantially tangent to the arcuate path traversed by an element 101 secured to the lever 75 to provide a surface for engaging the plungers.

The compression springs 95 and 96 are selected according to the range of yarn tensions accept-

able in operating a twister or other strand-handling machine. For example, if it is desired to operate the machine so that the cord tension may vary between 2000 and 1000 grams, the springs 95 and 96 are selected so that the combined moments with respect to the pivoting axis of the lever 75 of their compressive strength produce a force of 2000 grams at the point where the cord passes around the pulley 37 to resist cord tension which tends to pull the lever 75 out of its neutral position. The expansion of the spring 95 is not limited to the normal operating position of the lever 75. The spring 95 has a compressive strength such that it expands and moves the portion of the lever 75 to which the pulley 37 is attached downward when the cord tension drops below 1000 grams. Assuming for purposes of explanation that the moments of the cord tension and the spring tensions are applied at the same distance from the pivot axis of the lever 75, springs 95 and 96 are selected having strengths of 1000 grams each. Obviously, it takes 2000 grams of force to compress them simultaneously but as the plunger 99 cannot move beyond the position permitted by a stop-nut 103, the lever remains stationary in its normal operating position against the head of the plunger 99 between cord tensions of 1000 and 2000 grams. When the tension falls below 1000 grams, the spring 95 expands, carrying the lever 75 downward to operate the stopping switch 65.

While the invention has been disclosed with respect to the doubling together of two yarns, it is applicable as well as to the doubling or combining of more than two yarns into a single cord. It may be used also in any single strand-handling machine. It is of particular utility, however, in connection with machines which handle two or more strands simultaneously since the springs of the device may be regulated in accordance with the reduction in the cord tension brought about by the breakage of a single strand. Moreover, by fastening the tail-end of a supply package so that the end cannot be pulled through without tripping the stopping mechanism, laborious relacing of the twister is avoided.

In the specification, "doubling" is meant to include the folding or twisting of a singles and the twisting together of two or more individual strands and it is not intended to be restricted to the twisting together of two strands.

It is to be understood that changes and variations may be made without departing from the spirit and scope of the invention as defined by the appended claims.

I claim:

1. A stopping device for a strand-handling machine comprising a controller for stopping the machine, a movable member having a path of movement of predetermined range connected with the controller, resilient means for controlling the movement of the member between an intermediate position along the range and one end thereof, and other resilient means of appreciably different tension for controlling the movement of the member between said position and the other end of the range.

2. A stopping device for a strand-handling machine comprising a movable member for actuating control means of the machine having a predetermined movement range in which an intermediate position of the member permits operation but out of which the member engages stopping means of the machine, resilient means engaging the member and controlling its movement be-

tween an intermediate position along the range and one end thereof, and second resilient means of appreciably different tension for controlling the member between said position and the other end of the range.

3. A stopping device for a strand-handling machine comprising a movable member for actuating control means of the machine having a range of movement along which there is an intermediate position of the member permitting operation of the machine, resilient means for engaging and controlling the movement of the member between an intermediate position of the movement range and one end thereof at strand tension in excess of a desired tension range, detent means for limiting the deformation of the first resilient means to said portion of the movement range, and second resilient means adjusted and set to tension appreciably less than the first resilient means for controlling the movement of the member between said position and the other end of the movement range.

4. A stopping device for a machine for handling strands at tensions within a desired range comprising a movable member for actuating control means of the machine having a predetermined range of movement and having a portion adapted for passage of the strand therearound, resilient means for controlling the movement between an intermediate position of the movement range and one end thereof at tensions greater than the desired tension range, detent means for limiting the deformation of said first resilient means to said portion of the movement range, and second resilient means for controlling the movement of the member between said position and the other end of the movement range.

5. A stopping device for a strand-handling machine driven by an electrical means comprising a switch for controlling the flow of electrical power to the machine, switch-actuating means in contact with the strand so as to be pulled in proportion to the tension in the strand, resilient means for engaging the actuating means at its operating position and resisting the movement of the actuating means in response to the pull of the strand and deforming to permit movement of the actuating means only at strand tensions greater than a desired operating range, and second resilient means connected with the actuating means also resisting movement of the actuating means to a lesser extent such that deformation of the second resilient means occurs also at strand tensions less than the desired operating range.

6. A stopping device for a strand-handling machine driven by electrical means comprising a switch for controlling the flow of current to the drive means, a pivotable lever having its pivoting axis spaced with respect to the switch, means extending from portions of the lever spaced at opposite sides of the pivot axis to a region in close proximity of the switch whereby movement of the lever about the pivot axis from a neutral position will produce engagement of the means with the switch, and resilient means for holding the lever in the neutral position in opposition to the force exerted on the lever by a strand passing around a portion of the lever, said resilient means deformable only by movement of the lever produced by variations in the force exerted by the cord above or below a desired range.

7. A stopping device for a strand-handling machine driven by electrical means comprising a circuit-interrupting means for controlling the

flow of electrical power to the machine, a pivotable support lever having its pivoting axis spaced with respect to the circuit-interrupting means, elements extending from the portions of the lever spaced at opposite sides of the pivot axis to a region in close proximity to the circuit-interrupting means whereby tilting of the lever in either direction places either element into engagement with the circuit-interrupting means, a pulley rotatably attached near the end of the lever, resilient means connected to the lever and arranged to yield and permit movement of the lever with respect to the pivotal axis in one direction when a desired range of cord tension applied to the lever at the pulley is exceeded, and second resilient means attached to the lever for yieldably resisting a force less than that of the desired range applied to the lever at the pulley and moving the lever about its pivotal axis in an opposite direction to the movement produced by the first-named resilient means.

8. A stopping device for a strand-handling machine driven by an electrical means comprising a switch for controlling the flow of electrical power to the machine, a switch-actuation means in contact with the running strand responsive to a pull therefrom in proportion to the tension in the strand, resilient means connected with the actuating means and a stationary anchoring point of such strength that it is extended only by movement of the actuating means from a neutral position resulting from tension in the strand in excess of a desired range for operating the machine, and second resilient means of less strength than the first named resilient means for moving the actuating means in an opposite direction from the neutral position when the tension in strand falls below the desired operating range.

9. A stopping device for a strand-handling machine driven by an electrical means comprising a switch for controlling the flow of electrical power to the machine, a switch-actuating means in contact with the running strand for receiving a pull from the strand in proportion to the tension therein, resiliently compressible means extending between the actuating means and a stationary frame member spaced from the side of the actuating means from which the pull of the strand is applied, detent means for limiting the extension of the compressible means to an intermediate position of the switch-actuating means wherein the switch is maintained in a closed circuit position, and resiliently extensible means adjusted and set to exert less force than the compressible means extending between the actuating means and a stationary frame member spaced from the side of the actuating means opposite that of the compressible means, said compressible and extensible means having such set and adjustment that in combination they prevent movement of the actuating means from an intermediate position except that produced by strand tensions greater than a desired range, and for strand tensions less than the range the extensible means contracts and thereby moves the actuating means while the compressible means is prevented from expanding by the detent means.

10. A stopping device for a strand-handling machine driven by an electrical means comprising a switch for controlling the flow of electrical power to the machine, a switch-actuating means in contact with the running strand for receiving a pull from the strand in proportion to the tension therein, resiliently compressible means extending between the actuating means and a sta-

tionary frame member spaced therefrom in the direction from which the pull of the strand is applied to the actuating means, detent means for limiting the expansion of said compressible means to a degree corresponding to an intermediate position of the actuating means which permits operation of the machine, second resiliently compressible means extending also in a direction to oppose the pull of the strand on the actuating means and having an expansion range beyond the intermediate position of the switch-actuating means, said first and second compressible means having such set and adjustment that in combination they prevent movement of the activating means from the intermediate position except that produced by strand tensions exceeding a desired range, and for strand tensions less than the range, the second compressible means expands and thereby moves the actuating means while the first compressible means is prevented from expanding.

11. A stopping device for a strand-handling machine driven by an electrical means comprising a switch for controlling the flow of electrical power to the machine, a switch-actuating means in contact with the running strand and receiving a pull from the strand in proportion to the tension therein, a lever pivotably supported near one end with its other rotatable toward the actuating means, a tie-rod in slip-connection with the actuating means and the lever which limits the maximum spacing therebetween but permits swinging of portions of the actuating means and the lever toward each other and a detent for limiting the swinging of the lever away from the actuating means, a spring connecting swingable portions of the actuating means and the lever, and another spring substantially aligned with the first spring extending away from the lever in an opposite direction and secured to a stationary anchoring means, said second spring adjusted and set to a tension equal to the pull exerted on it by the lever and the actuating means resulting from tension in the cord applied to the actuating means at the upper limit of a desired tension range, and said first spring set and adjusted to a tension equal to the pull to which it is subjected by strand tension acting on the actuating means at the lower limit of said range.

12. A stopping device for a strand-handling machine driven by an electrical means comprising a switch for controlling the flow of electrical power to the machine, a lever pivotably supported at a point near one end thereof in spaced relationship with the switch, means for guiding a strand around another portion of the lever, elements pivotally secured at points equi-distant on opposite sides of the pivot axis of the lever and extending toward a button for operating the switch, a stationary guide for supporting the elements in alignment for engaging the button, a second lever pivotably supported at one end thereof substantially parallel with the first lever, a tie-rod in slip-connection with swingable portions of the two levers and limiting rotation of the levers away from each other but not restricting the rotation thereof toward each other, a spring connecting swingable portions of the levers, a second spring extending away from the second lever in a direction opposite to that taken by the first spring and having its other end secured to a stationary anchoring means, said first spring set and adjusted to a tension less than the pull transmitted to it through the first lever as a result of tension in the strand within a desired

11

tension range for operating the machine, and the second spring set and adjusted to a tension such that it is extended only by a pull resulting from a strand tension greater than the desired operating strand tension range transmitted to it through the levers linked together by the tie-rod and the first spring.

13. A stopping device for a strand-handling machine driven by electrical means comprising a switch for controlling the flow of electrical power to the machine, a lever pivotably supported along a portion thereof, elements pivotably secured to the lever at points in opposite directions from the pivoting axis extending toward a button for operating the switch, guide means for bringing the elements into engagement therewith, means connected with another portion of the lever for guiding the strand and for translating the tension therein into a pull tending to move the lever about its axis, a stationary frame member spaced from the side of the lever from which the path of the strand extends, two parallel plungers passing through and supported by the frame member and engaging the lever, springs on each of the plungers for urging them toward the lever, detent means on one of the plungers for limiting its motion in response to the force imposed by the spring to an extent corresponding to the position of the lever in which neither element contacts the switch button, said springs having a combined strength which prevents the lever from moving and actuating the switch while subjected to a pull resulting from strand tension in a desired operating range, and the spring of the unrestricted plunger of such adjustment and set that it remains compressed within the desired strand tension range but expands to move the lever into switch-operating position if the strand tension falls below the range.

14. A stopping device for a strand-handling machine driven by an electrical means comprising a switch controlling the flow of electrical

12

power to the machine, a lever pivotably supported along a portion thereof, elements pivotably secured to the lever at points spaced in opposite directions from the pivoting axis of the lever extending toward a button for operating the switch, means for guiding the elements into engagement with the button, means for guiding the strand about a portion of the lever along a path such that tension in the strand is translated into a pull tending to move the lever about its axis, a stationary frame member spaced with respect to the side of the lever approached by the strand path, a second frame member on the opposite side of the lever, a plunger extending through and slidably supported in the first frame member, a spring which resists compression for urging the plunger toward the lever, a detent means on the plunger limiting the movement of the plunger to a point corresponding to the normal operating position of the lever for maintaining a closed switch, a spring which resists extension extending between the lever in the second named frame member, the two springs being adjusted and set to exert such force as to prevent movement of the lever when subjected to a pull resulting from strand tension within a desired tension range and to permit movement when the strand tension is greater than this range, and the force exerted by the spring which resists tension being such as to contract the spring and to move the lever in the event that the strand tension falls below the desired range.
